CLAIM

The ornamental design for thermal insulation for P-trap piping, as shown.

DESCRIPTION

FIG. 1 is a perspective view of the thermal insulation of the invention;

FIG. 2 is a side elevational view of the thermal insulation of the invention, the other side being a mirror image thereof;

FIG. 3 is a front view of the thermal insulation of the invention;

FIG. 4 is a rear view of the thermal insulation of the invention;

FIG. 5 is a top view of the thermal insulation of the invention; and,

FIG. 6 is a bottom view of the thermal insulation of the invention.
